(57) **CLAIM**

The ornamental design of a stand for electronic device and smart watch, substantially as shown and described.

DESCRIPTION

FIG. 1 is a front view of a stand for electronic device and smart watch in accordance with the present invention.

FIG. 2 is a rear view thereof.

FIG. 3 is a left end view thereof.

FIG. 4 is a right end view thereof.

FIG. 5 is a top view thereof.

FIG. 6 is a bottom view thereof.

FIG. 7 is a front perspective view thereof; and,

FIG. 8 is another perspective view thereof.
